UNITED STATES PATENT OFFICE

EDGAR E. BROSIUS, OF PITTSBURGH, PENNSYLVANIA

MUD GUN

Application filed February 10, 1932. Serial No. 582,084.

The present invention relates broadly to the iron and steel industry and more particularly to that phase thereof having to do with the proper operation of furnaces, such for example, as blast furnaces.

During the manufacture of ferrous materials, it is necessary after they have been reduced to the desired molten condition in a furnace to tap the same to permit the charge 10 to be drawn from the furnace. Necessarily the point at which the charge is withdrawn must be at a point sufficiently low to permit emptying the furnace to the desired extent. Thereafter it becomes necessary to effect closing 15 of the tapping opening.

Due to the high temperatures prevailing in the vicinity of a furnace of the character in question, any operation which must be manually performed in the vicinity of the 20 furnace, and more especially at a point where there is a possibility of molten metal breaking through the furnace and injuring the workmen, is dangerous. One of the objects of the present invention is to provide an improved form of apparatus for more nearly 25 automatically accomplishing the closing of an opening of the character referred to. Such forms of apparatus are customarily referred to in the art as mud guns, and specifically the invention may be considered as 30 relating to improvements in the construction, mounting and operation of such guns.

It is well understood by those skilled in the art that mud guns comprise means for 35 feeding a predetermined amount of a suitable clay-like material of proper consistency into a tapping opening. The feeding of the clay in order to provide an effective closure must be under such pressure as to not only 40 effectively seal the opening, but also to seal such opening against the full pressure conditions obtaining within the furnace. There is therefore involved the question of the 45 quantity of clay which may be fed, and the pressure under which the clay may be delivered into the opening.

A second requirement has to do with the ability to maintain the gun in the proper relative position to the furnace during the clay 50 feeding operation. If relative outward

movement between the gun and furnace is permitted at this time, a proper closure cannot be effected. Heretofore it has been customary to rely upon latches or clamping arms of one form or another for temporarily maintaining the gun in cooperative clay feeding relation to the furnace. Failure of the latch mechanism, or relative movement between any of the furnace parts and any of the latch parts, or any of the latch parts and the gun 55 60 may result in defeating the purpose intended.

The present invention has for another of its objects improvements both in the mechanism for bringing the gun into clay feeding 65 position, and for maintaining it in such position throughout the entire hole closing operation.

It is also customary in the art to provide a splasher plate in a position adjacent the 70 tapping hole or iron notch of the furnace resting on top of the trough for the purpose of preventing damage to the front of the furnace when metal is flowing. In order to move a mud gun into hole closing position, 75 it has heretofore been necessary to first separately move the splasher plate to inoperative position in order to permit the clay nozzle of the gun to approach and enter the tapping hole. This splasher plate moving operation 80 having been independent of the movement of the gun, has always presented the possibility either of too early a removal, with consequent damage to the front of the furnace, or too late a removal with possibility of 85 resultant injury either to the furnace, the mud gun, or both.

Another object of the present invention is to provide an operating connection between the gun and the splasher plate, whereby the 90 splasher plate is automatically moved in a predetermined timed relationship to the movement of the gun either to or from its operative hole closing position. In this respect it will be apparent that after a hole has 95 been closed, it is necessary to swing the gun bodily to such a position that it will not be subjected to the heat of the molten metal during a subsequent tapping operation. During such movement of the gun to inoperative 100

position the splasher plate is automatically moved into position over the trough, while during movement of the gun into operative position the splasher plate is moved in the opposite direction.

5 Still another object of the invention is to provide improvements in the mud gun structure whereby the parts having been moved into the required operative relationship, the desired quantity of hole closing material under the necessary pressure may be quickly fed into the tapping hole.

10 In the accompanying drawings I have shown more or less diagrammatically, and for purposes of illustration only, one embodiment of the present invention. In the drawings:

15 Figure 1 is a top plan view of one form of apparatus constructed in accordance with the present invention;

20 Figure 2 is a side elevational view of the apparatus illustrated in Figure 1, showing the gun in position for closing a tapping hole;

25 Figure 3 is a rear elevational view of the apparatus illustrated in Figure 1;

30 Figure 4 is a view similar to Figure 2 illustrating diagrammatically a modified embodiment of the splasher plate moving means;

35 Figure 5 is a view partly in longitudinal section and partly in elevation of the gun shown in Figures 1, 2 and 3;

40 Figure 6 is a view similar to Figure 5 but turned at 90° therefrom; and

45 Figure 7 is a detail sectional view along the line VII—VII of Figure 6.

Referring more particularly to Figures 1, 2 and 3 of the drawings, I have illustrated a portion of a furnace wall 2 with a tapping hole 3 formed adjacent the hearth portion thereof and adapted when open to deliver molten metal to an iron trough 4 through the space below a splasher plate 5 provided for the purpose of protecting the front of the furnace from injury due to splashing of the iron.

50 In a position adjacent the furnace wall and spaced laterally from the tapping hole there is indicated one of the furnace columns 6 around which extends a clamp or bracket 7 providing a bearing support for a shaft 8 carrying a gun supporting arm 9 which carries the gun G. Rigidly secured to the furnace wall in a plane above the plane of the tapping hole 3 is a bracket 10 in which is pivotally mounted one end of a tubular spacing sleeve 11 adapted to project outwardly from the furnace wall a predetermined distance and contact with the gun arm 9 when the gun is in operative position as shown in Figure 2 for positively limiting the travel of the gun toward the furnace.

55 In accordance with the present invention,

however, this spacing feature may be eliminated by providing a relatively shorter arm as will be hereinafter more fully apparent. Dead-ended to the arm 11 preferably at a point within the same is one end of a gun swinging cable 12. The free end of the gun swinging cable passes outwardly around a drum 14 to a guide 15 on the gun arm shaft 8 and thence over a pulley 16 to a counterweight or slack take-up mechanism 17.

70 Carried by the gun arm 9 is a gun swinging and positioning motor 18 the armature shaft of which is operatively connected to a worm 19 in mesh with a worm wheel 20 on a drum shaft 21 carrying the drum 14.

75 With the parts in the position illustrated in

Figure 1, assuming a counterweight 17 or slack adjusting mechanism of proper weight or construction, if the motor 18, which is of the reversible type, is rotated in such direction as to turn the drum 14 in a clockwise direction as viewed in this figure, the gun arm and the gun will be bodily swung from the full line position indicated in this figure into the dotted line or inoperative position. With

80 the parts in the dotted line position, rotation of the motor in the opposite direction will move the gun into its full line position. It will be understood that in order to give to the gun the desired modified path of travel

85 required to permit such movement into and out of operative position, I may utilize a movement modifying or compensating means of suitable construction such, for example, as

90 the link "18" and its operating connections as disclosed in my Patent No. 1,265,602 of

95 May 7, 1918. There will also preferably be utilized a suitable tilting means for the gun, such as a tilting cable 22 corresponding to the member 18 of Berg Patent No. 1,121,224

100 of December 15, 1914.

During movement into operative position, with a spacer 11 of the length illustrated for example in Figures 1 and 2, the gun arm will contact the outer end of the spacer in such

110 manner that further inward movement of the gun will be precluded. Thereupon, continued operation of the motor 18 will tighten the portion of the gun swinging cable 12 ex-

115 tending between the drum 14 and the point at which the cable is dead-ended on the spacer, thereby placing this portion of the cable under sufficient tension for precluding any outward movement of the gun. Due to

120 the use of a worm driving connection between the motor 18 and the drum 14, it is possible by utilizing such a pitch that the worm is ir-

reversible, to positively lock the drum 14 against undesired rotation at this time, and thereby preclude any outward movement of

125 the gun.

It will be understood that in accordance with the present invention, I utilize a common mechanism for both swinging the gun and locking the gun in operative position, the

holding function becoming effective immediately upon the conclusion of the swinging function, thereby obviating any time interval such as heretofore required for the proper operation of supplemental latching or clamping means. In this manner, it is possible to move the gun into operative position and secure it against movement from this position in much less time than has heretofore been considered possible, and to accomplish this dual function with a single mechanism and driving means.

The connection between the gun G and the arm 9 preferably comprises a suitable pivotal mounting 23 as illustrated more particularly in Figure 2, such a mounting permitting the desired tilting of the gun. The pivotal mounting 23 is preferably supported from the gun arm 9 through the medium of a suitable bearing, such as an anti-friction bearing 24 permitting the necessary swivelling movement between the gun and the arm as required by the compensating mechanism or path modifying mechanism before referred to.

In accordance with the present invention, the gun G, as illustrated more particularly in Figures 5 and 6, provides a main clay barrel 25 of generally cylindrical contour having a charge opening 26 adapted to be closed at will by a suitable closure plate 27. Carried by the front of the clay barrel 25 is a nozzle 28 of the desired configuration to properly cooperate with the tapping hole 3. This nozzle in accordance with my invention is preferably carried by a pivot 29 permitting the nozzle to be swung at will into the dotted line position of Figure 6, as may be required for properly cleaning the same. For locking the nozzle in alignment with the clay barrel, there may be provided a pin bracket 30 through which extends a locking pin 31 into engagement with an opening 32 in the nozzle. Thus, by merely moving the pin 31 the nozzle may be released for swinging movement, or locked in alignment with the barrel preparatory to a clay feeding operation.

Secured to the opposite end of the barrel through the medium of upper and lower removable pins or keys 33 and 34, respectively, is a gear housing 35. Projecting rearwardly from the gear housing is a bracket 36 carrying a gun motor 37. Within the clay barrel is a piston 38 having projecting rearwardly therefrom through the gear housing 35 and bracket 36 a piston in the form of a rack 39. While this rack may be of either single or double construction, i. e., provided either with teeth on one or both sides thereof, I preferably utilize a double rack as shown more particularly in Figure 7 of the drawings. Mounted within the gear housing 35 on suitable shafts 40 and 41 are rack pinions 42 and 43 meshing respectively with the rack teeth on opposite sides of the rack and con-

stituting a symmetrical driving means therefor.

Secured to the shafts 40 and 41 above the rack are timing pinions 44 and 45 insuring synchronous or timed rotation of the shafts 40 and 41 and therefore of the rack pinions 42 and 43. For driving these shafts and pinions, the shaft 40 may be provided with a worm wheel 46 with which meshes a worm 47 carried by a jack shaft 48. This jack shaft is driven by the motor 37 through suitable reduction gearing 49.

The barrel having been filled with clay, and the gun moved into its operative position of Figure 2, the motor 37 is energized for advancing the piston 38 and thus expelling the contents of the barrel through the nozzle 28 into the tapping hole. This barrel is preferably of such capacity as to provide more than sufficient clay for any average hole closing operation and a sufficient reserve supply to take care even of the unusual conditions sometimes encountered. After the desired amount of clay has been discharged from the gun, the motor 37 may be stopped, and the gun held in the position shown in Figure 2 for a sufficient length of time to insure setting of the clay. During this setting time, it will be understood that the gun construction must be such as to withstand the pressure conditions within the furnace.

To this end, I preferably utilize an irreversible worm 47 capable of positively locking the piston 38 in the position to which it has been moved by the motor, so that the piston constitutes a positive abutment against which the clay may not move backwardly. The desired setting time having elapsed, the gun may be swung to its inoperative dotted line position of Figure 2, the nozzle 28 released and swung to its dotted line position of Figure 6 and easily cleaned before opportunity is afforded for undue solidification of the clay remaining therein.

If it is desired for any reason to effect separation of the clay barrel from its operating mechanism, it is merely necessary to withdraw the pins or keys 33 and 34, whereupon the housing 35, motor 37 and piston 38 with their respective associated parts may be bodily removed from the barrel. It will thus be seen that ready access to either end of the barrel may be had at the will of the operator. It will further be noted that the construction is such that the gear housing 35 constitutes the closure for the rear end of the clay barrel. This closing function is performed primarily by a face plate 50.

By reference, however, to Figure 5 of the drawings, it will be noted that the construction of the parts is such as to provide an opening 51 adjacent the rear bottom portion of the clay barrel through which any clay leaking past the piston may be readily discharged

- to a point exteriorly of the gun or its operating parts. To preclude the possibility of such leakage clay from getting between the teeth of the rack 30, I preferably provide the 5 rack with a shield plate 52 overlying the same throughout its length and of slightly greater width than the rack, so that clay leaking past the upper portion of the piston and dropping downwardly will be caught by the shield.
- 10 Upon the reverse movement of the rack, any accumulated clay on the shield will be scraped therefrom by the face plate 50 and discharged through the opening 51.

Reference has heretofore been made to the 15 fact that the rack 39 extends completely through the bracket 36. In actual practice, this bracket will preferably be of such construction as to provide a complete housing or enclosure for the rack, thereby protecting it 20 not only against possible accumulations of foreign material, but also against the heat of the trough and the possibility of any molten metal splashing onto or injuring the same. During the swinging movements of 25 the gun, this bracket enclosure likewise protects the rack against mechanical injury. For partially assisting in guiding the rack during its movements, I preferably provide therefor a roller support 53 carried by the 30 gear housing 35 within a shield 54 and preferably at a point adjacent the junction between the gear housing and the motor bracket.

It will also be apparent to those skilled in 35 the art that by mounting the motor 37 above the bracket 36 and providing, if desired, a heat shield plate 55 between the bracket and the motor, the operating parts of the motor are completely protected from injury by reason of excessive temperature conditions. 40 The construction is such that not only is the clay barrel, which is least susceptible to injury, in a position adjacent the maximum heat and the operating parts in a position 45 remote from such heat, but that the motor is further elevated appreciably with respect to the trough and thereby additionally protected. This further enables the worm 47 and worm gear 46 to be located at a point remote 50 from the heat of the trough whereby it is possible to maintain proper lubrication there- 55 for at all times.

It has heretofore been proposed in the art to effect the forward movement of a piston of 60 the general character herein contemplated by means of a suitable screw and actuating connections. In practice, however, it has been found that the rotative tendency of the screw is transmitted to the piston in such 65 manner that it is necessary to provide special guiding means for the piston itself, such guiding means necessarily being located within in the body of the clay barrel. By utilizing a rack, this rotative tendency is entirely obvi- 70 ated so that the interior of the clay barrel

may be maintained entirely free from any such guiding means.

Reference has heretofore been made to the 70 splasher plate 5. This splasher plate at one side thereof is provided with a pivotal mounting 56 permitting the same to be swung to inoperative position. For swinging the splasher plate, it is provided with an eye 57 within which is connected a cable 58 passing 75 upwardly from the splasher plate around a guide 59 and thence to an arm 60 projecting outwardly from the upper end of the shaft 8. Cooperating with the pulley 59 may be a guide 80 roller 61 effective for maintaining the cable in the pulley groove, the pulley 59 being mounted in a suitable bracket 62 secured to the furnace column 6. When the gun moves from its inoperative dotted line position of Figure 1 to its operative full line position, the arm 60 will exert tension on the cable 58, thereby lifting the splasher plate, the speed of lifting being synchronized to the swinging speed of the gun. Upon movement of the parts in the reverse direction, the splasher plate will be lowered synchronously with the 85 swinging speed of the gun parts. In this manner possibility of damage by collision 90 between the parts is precluded.

In Figure 4, I have illustrated a slightly 95 modified embodiment of the invention, wherein in the nozzle 28' of the gun is shown as having a cam track 63 thereon of such construction as to engage under the splasher plate 5' and gradually lift the same as the gun is swung 100 into position. Due to the location of the motor and its operating parts entirely rear- 105 wardly of the pivotal mounting 23 as shown in Figure 2, it is a comparatively simple matter to sufficiently over-counterbalance the weight of the forward portion of the gun in such manner that the gun may carry the additional weight of the splasher plate without disturbing the proper position of the gun. In this manner the splasher plate may be 110 operated directly by the gun in predetermined relationship to the gun position.

The advantages of the present invention 115 arise from the provision of an improved gun structure having improved positioning and holding means therefor, whereby a single mechanism may be utilized for not only swinging the gun into operative position, but for automatically holding it against movement from such position.

Still further advantages arise from means 120 whereby a predetermined relationship between the position of the gun and the splasher plate may be insured.

Other advantages arise from the various 125 details of construction and operation as herein set forth.

While I have herein illustrated and de- 130 scribed certain preferred embodiments of the present invention, together with preferred features of construction, it will be understood

that changes in the construction and operation of the parts may be made without departing either from the spirit of the present invention or the scope of my broader claims.

I claim:

5. 1. In a mud gun, a clay barrel, and a pivotally mounted nozzle on the discharge end of said barrel.
2. In a mud gun, a clay barrel, a piston therein, and operating means for the piston including a gear housing detachably secured to said barrel.
3. In a mud gun, a clay barrel, a piston therein, and operating means for the piston including a gear housing detachably secured to said barrel, at points above and below the barrel only.
4. In a mud gun, a clay barrel, a piston therein, operating means for said piston including a gear housing detachably secured to said barrel, and a motor bracket projecting rearwardly from said housing.
5. In a mud gun, a clay barrel, a piston therein, operating means for said piston, including a gear housing detachably secured to said barrel, and a motor bracket projecting rearwardly from said housing, there being a motor supported on and above said bracket.
6. In a mud gun, a clay barrel, a piston therein, operating means for the piston including a gear housing detachably secured to said barrel, and a piston rod comprising a rack movable through said housing.
7. In a mud gun, a clay barrel, a piston therein, operating means for the piston including a gear housing detachably secured to said barrel, a motor bracket projecting rearwardly from said housing, a motor mounted on said bracket, and a piston rod comprising a rack movable through said housing and bracket below the motor.
8. In a mud gun, a clay barrel, a piston therein, operating means for the piston including a gear housing detachably secured to said barrel, a motor bracket projecting rearwardly from said housing, a motor mounted on said bracket, and a piston rod comprising a rack movable through said housing and bracket below the motor, said bracket constituting a protective enclosure for said rack.
9. In a mud gun, a clay barrel, a piston therein, and operating means for the piston including a gear housing detachably secured to said barrel, said gear housing and barrel providing an opening therebetween for the discharge of clay passing the piston.
10. In a mud gun, a clay barrel, a piston therein, a piston rod, means for moving said piston rod, a shield overlying said piston rod for preventing clay passing the piston from dropping onto said rod, and means for scraping such clay from the shield.
11. In a mud gun, a clay barrel, a piston therein, a piston rod, means for moving said piston rod, a shield overlying said piston rod
- for preventing clay passing the piston from dropping onto said rod, and means for scraping such clay from the shield, there being a discharge opening adjacent the rear of said barrel for such clay.
12. In a mud gun, a clay barrel, a piston in said barrel, a rack for moving said piston, and motor means located above the plane of said rack for driving the same.
13. In a mud gun, a clay barrel, a piston therein, a rack secured to and projecting from said piston, and means for driving said rack in either direction.
14. In a mud gun, a clay barrel, a piston therein, a rack secured to and projecting from said piston, and means for driving said rack in either direction, said means including a worm and worm wheel above the plane of said rack.
15. In a mud gun, a clay barrel, a piston therein, a rack projecting rearwardly from said piston for moving the same, and driving means for said rack including a worm, worm gear and motor above the plane of said rack.
16. In a mud gun, a clay barrel, a piston therein, a rack projecting rearwardly from said piston for moving the same, and driving means for said rack including a worm, worm gear and motor above the plane of said rack and rearwardly of said barrel.
17. In a mud gun, a support, a gun arm and gun swingingly carried by said support, and common means for swinging said gun arm and gun into operative hole closing position and holding the same against movement from such position.
18. In a mud gun, a support, a gun arm and gun swingingly carried by said support, and common means for swinging said gun arm and gun into operative hole closing position and holding the same against movement from such position, said means including a single cable and drum around which the cable passes.
19. In a mud gun, a support, a gun arm and gun swingingly carried by said support, and common means for swinging said gun arm and gun into operative hole closing position and holding the same against movement from such position, said means including a single cable and drum around which the cable passes, together with a motor mounted on said gun arm for rotating said drum.
20. The combination with a furnace, of a mud gun support, a gun arm swingingly secured to said support, a gun carried by said arm, a splasher plate, and means for simultaneously moving said gun and splasher plate.
21. The combination with a furnace having a tapping opening and iron trough, of a splasher plate for said trough, a mud gun movable relatively to said trough, and means for insuring simultaneous movement of said gun and splasher plate.
